UNITED STATES PATENT OFFICE

JOHANN MAHLER, OF AUGSBURG, GERMANY, ASSIGNOR TO MASCHINENFABRIK AUGSBURG-NUERNBERG, AKTIENGESELLSCHAFT, OF AUGSBURG, GERMANY, A GERMAN CORPORATION

FUEL-CHARGING PUMP

Application filed March 8, 1926. Serial No. 93,170, and in Germany February 11, 1926.

This invention relates to fuel charging pumps for combustion engines and more particularly to the regulation of such pumps. According to this invention the shaft, which carries the cams for operating the fuel pump, is made of hollow conformation, and serves for receiving the longitudinally displaceable governor rod, which transmits the regulating motion to the pump. By this arrangement the necessity of mounting the rod mechanism on the outside, which may easily give rise to a bending of the mechanism or other injuries thereof, will be obviated and a simple and reliably operating construction will be the result.

By reason of the arrangement of the regulating rod inside of the hollow cam-shaft the governor may be built into the driving gear for the cam-shaft, so that it will be positioned within the two-part gear-box. The dividing surface of the gear-box will thereby be positioned in the center of the cam-shaft. It will thus also be possible to take the entire pump mechanism together with the cam-shaft and the governor away from the engine solely by removing a few screws, and to eventually replace said pump mechanism by another. This is of especial importance for vehicle motors, in case the pump mechanism will be damaged during travel. In this case the entire pump mechanism may be replaced within a very short time, and a reserve pump mechanism inserted instead thereof.

In the drawing an example of the new fuel charging pump according to this invention is shown, Fig. 1 being a side view of the novel device, partly shown in longitudinal section, and Fig. 2 a section according to line A—B of Fig. 1.

The cam-shaft *a*, which carries the driving cams *b* for the operation of the pump pistons *c* of the fuel pump is made of hollow conformation. The governor rod *d* is mounted within the cam-shaft *a*, said rod being displaced under the influence of the governor during increase of the speed of the engine above normal and again carried back into its original position during a decrease of the speed by action of the spring

f which surrounds the governor rod *d*. The governor *e* is placed within the driving gear *g* for the cam-shaft *a* and consists of two fly-balls *h*, which are rotating around the pivots *i* of the hub of the driving gear *h* and act upon the governor rod *d* by means of the angle arms *j*. The driving gear *g* is mounted together with the governor *e* in a two-part gear-box *k*, whose dividing surface *k¹*, for reasons hereinafter explained, is in a plane with the axis of the cam-shaft *a*.

The governor rod *d* upon being adjusted by the governor *e* acts upon a bell-crank lever *m* which is pivotally mounted at *l*, said lever *m* transmitting the motion to a rack *n* and by way of a gear *o* meshing with the latter to a controlling shaft *p*. Upon this shaft *p* there are eccentrically mounted levers *q* which act upon the overflow-valves *s* of the fuel pump by means of adjustable stops *r*. If the speed of the engine rises above normal, the outwardly moving fly-balls *h* of the governor *e* will cause a displacement of the governor rod *d* towards the left, the bell-crank lever *m* will transmit the motion to the rack *n* and the gear *o*, whereby the shaft *p* will be rotated. By this the point of rotation of the lever *q* will be lifted or lowered, so that the stop *r* will cause the overflow valve appertaining thereto to open sooner or later, said valve causing the drawn-in fuel to be by-passed to the overflow chamber *s'* during the remaining part of the stroke of the pump and to thereby terminate the injections through the injection passage *c'*. The levers *q* extend beyond the stops *r* and are provided with rollers *y*, by means of which said levers act upon the pump piston *c*. Besides, these levers will be supported by means of rollers *x* on a plane running surface *w* provided on the levers *t*, which are again eccentrically mounted upon a regulating shaft *u* and controlled by means of rollers *v* from the driving cams *b* of the cam-shaft *a*. The transmission of the motion of the cams *b* to the pump pistons *c*, therefore, takes place by way of the levers *t* and *q*. By rotating the shaft *u* the levers *t* are adjusted in longitudinal or horizontal direction and by this

the moment, at which the rollers v come in contact with the curved surface of the cams b will be changed and therewith also the moment at which the injection commences.

5 In consequence of the levers q being supported by the plane surface w , the position of these levers will not be influenced by the adjustment of the levers t .

The governor rod d will be acted upon 10 in addition to the spring f by an auxiliary spring 1 , which is mounted within a casing 2 , and whose tension may be changed by screwing the cover 3 of the casing to a greater or smaller extent into or out of its guide 15. By means of this spring the resistance offered by the governor rod d against being adjusted may be changed at will, so that the action exerted by the governor upon the adjustment of the admission will come into 20 play only after the engine has attained a certain predetermined speed. The additional spring 1 will therefore act as a means for regulating the speed of the engine.

The entire fuel pump is mounted laterally 25 of the engine frame 5 and rests upon the base 6 , to which it is detachably fastened by screws 7 . After unscrewing these screws and removing the cover k^2 of the gear-box, the entire pump including governor e and 30 driving gear g for the cam-shaft a may be taken off the engine and eventually replaced by a spare fuel pump, since the dividing surface of the gear-box is situated in the same plane as the axis of the cam-shaft a . 35 In this manner interruptions of the service for some longer time cannot take place, if troubles arise in the fuel pump.

I claim:

1. A fuel pump for an internal combustion engine of the character described, comprising fuel feeding means, a hollow cam-shaft for driving said fuel feeding means, and means for controlling the degree of fuel admission, said fuel admission controlling means including a governor, a governor rod positioned within said hollow cam-shaft, a bell-crank lever operated by said governor rod, a rack operated by said bell-crank lever, a gear meshing with said rack, and a 45 controlling shaft fixed to said gear adapted to transmit the motion of the governor rod to rock said controlling shaft for adjusting the admission.

2. A fuel pump for an internal combustion engine of the character described, comprising fuel feeding means, a hollow cam-shaft for driving said fuel feeding means, and means for controlling the degree of fuel admission, said fuel admission controlling 55 means including a governor, a governor rod positioned within said hollow cam-shaft, a controlling shaft, a lever eccentrically arranged upon said controlling shaft, an operative connection between said governor rod and said controlling shaft, a relief valve for

said pump, and an adjustable stop provided on said lever and adapted to cooperate with said relief valve.

3. A fuel pump for an internal combustion engine of the character described, comprising fuel feeding means, a hollow cam-shaft for driving said fuel feeding means, means for adjusting the starting moment of the fuel injection, including an eccentrically mounted lever interposed between said cam-shaft and said fuel feeding means, and means for controlling the degree of fuel admission, including a governor, a governor rod positioned within said hollow cam-shaft, a second eccentrically mounted lever interposed between said cam-shaft and said fuel feeding means for controlling the admission, and an operative connection between said governor rod and said second eccentrically mounted lever.

4. A fuel pump for an internal combustion engine of the character described, comprising a pump plunger, a hollow cam-shaft for driving said pump plunger, means for controlling the degree of fuel admission including a governor, a governor rod positioned within said hollow cam-shaft, a controlling lever for adjusting the admission, and operative connections between said governor rod and said controlling lever; and means for controlling the beginning of fuel injection, including a regulating lever; said controlling lever and said regulating lever being both interposed between said cam-shaft and said pump plunger to transmit the motion of the cam-shaft to the pump plunger.

5. A fuel pump for an internal combustion engine of the character described, comprising means for controlling the beginning of fuel injection, and means for controlling the degree of fuel admission, said means including a plurality of levers, a pump plunger controlled by one of said levers, a relief valve controlled by another of said levers, a cam-shaft, said levers being interposed between said cam-shaft and said pump plunger, one of said levers having a plane surface with which another of said levers contacts and through which motion is imparted from the cam-shaft to the pump plunger, and means for adjusting the fulcrum points of said levers along lines displaced a considerable distance apart.

6. A fuel pump for an internal combustion engine of the character described, comprising means for controlling the beginning of fuel injection, and means for controlling the degree of fuel admission, said means including a plurality of adjacent levers, a pump plunger controlled by one of said levers, a relief valve controlled by another of said levers, means for adjusting the fulcrum point of said first-named lever to vary the beginning of stroke of said pump plunger

in relation to the cycle of engine operation, means for adjusting the fulcrum point of said second-named lever in a direction substantially 90° from the direction of adjustment of the fulcrum point of the first-named lever to vary the degree of actuation of the relief valve, a cam-shaft, said levers being interposed between said cam-shaft and said pump plunger, one of said levers having a plane surface extending substantially in the plane of adjusting movement of said lever, said other lever contacting with said plane surface and imparting therethrough movement to said pump plunger, the parts being so constructed as to permit the degree of fuel admission and the beginning of fuel injection to be varied independently of each other.

7. A fuel pump for an internal combustion engine of the character described, comprising means for controlling the beginning of fuel injection, and means for controlling the degree of fuel admission, said means including a plurality of levers, a pump plunger controlled by one of said levers, a relief valve controlled by another of said levers, means for adjusting one of said levers to vary the beginning of stroke of said pump plunger in relation to the cycle of engine operation, means for adjusting another of said levers in a direction substantially 90° from the adjustment direction of said one lever to vary the degree of actuation of said relief valve, a cam-shaft, a driving connection between said cam-shaft and said first-named lever, said first-named lever having a plane surface thereon extending substantially in the plane of adjusting movement of said lever, a driving connection between said second-named lever and said plane surface, and a driving connection between said second-named lever and said pump plunger, said parts being so constructed that adjustment of either lever and consequent movement of its associated parts imparts substantially no change of adjustment to the other lever and its associated parts.

8. A fuel pump for an internal combustion engine of the character described, comprising means for controlling the beginning of fuel injection, and means for controlling the degree of fuel admission, said means including a plurality of eccentrically mounted levers, a pump plunger, a relief valve, one of said levers controlling the beginning of actuation of said pump plunger in relation to the cycle of engine operation to control the beginning of fuel injection, an adjustable stop carried by another of said levers adapted to cooperate with said relief valve to control the degree of fuel admission, means for adjusting said first-named lever on its eccentric mounting to vary the beginning of actuation of said pump plunger.

er, means for adjusting said second-named lever on its eccentric mounting in a direction substantially at right-angles to the direction of adjusting movement of said first-named lever to vary the degree of actuation of said relief valve, a cam-shaft, a roller carried by said first-named lever in driving connection with said cam-shaft, said first-named lever having a plane surface thereon extending substantially in the direction of its adjusting movement, a roller carried by said second-named lever in driving engagement with said plane surface, and a second roller carried by said second-named lever in driving connection with said pump plunger, the parts being so constructed that the beginning of fuel injection and the degree of fuel admission may be adjusted independently of each other.

9. In an internal combustion engine of the character described having an engine frame, a fuel pump detachably mounted on said engine frame, a hollow driving shaft for said pump extending to the exterior of said pump, a hollow driving gear mounted adjacent one end of said shaft on the exterior of said pump; a governor for said pump including a governor rod positioned within said hollow driving shaft, and a governor weight positioned within said hollow driving gear and operatively connected with said governor rod; and a two-part gear case enclosing said shaft end, driving gear and said associated governor parts, the construction being such as to permit said pump, driving shaft, driving gear, and governor to be dismounted from or mounted on said engine frame as a unit.

10. A fuel pump for an internal combustion engine of the character described, comprising a casing, fuel feeding means therein, a controlling shaft mounted within said casing, for controlling the degree of fuel admission, a hollow cam-shaft within said casing spaced from said controlling shaft and paralleled therewith, a governor rod within said hollow cam-shaft, a governor weight at one end of said governor rod for actuating the same, and an operative connection in said casing at the other end of said governor rod between said controlling shaft and said governor rod, the construction being such as to permit the removal of the pump as a unit with the controlling shaft, hollow cam-shaft, governor rod and said operative connection in their operative assembled positions.

In testimony whereof I have affixed my signature.
